MARIAN ROMANOWICZ AND JOHANN ROMANOWICZ, OF VIENNA, AUSTRIA.

PHOTOGRAPHIC FILM OR PLATE PACK.

Application filed May 19, 1927, Serial No. 192,614, and in Austria May 25, 1926.

Exchange packs of photographic plates have been proposed in which each rigid or flexible plate of glass, celluloid or any other suitable material is provided at its side remote from that exposed to light, that is to say its back side with a backing sheet, a pulling strip and a protecting sheet all of which are attached to the front edge of the plate and are so arranged that the backing 10 plate is located between the plate and the pulling strip, the latter between the backing sheet and the protecting sheet and the latter is in direct contact with the next lower plate. The plates are superposed to form a pile, 15 the backing sheet and the pulling strip of the uppermost plate extending downwards on the back side of the pile and then extending forwards below the backing sheet and pulling strip of the next lower plate and 20 so on. The pulling strips project forwards and outwards through a slot through which they may be pulled out, but the lower front ends of the backing sheets are prevented from moving forwards.

25 The protecting sheets have substantially the same size as the plates. Owing to this arrangement they can be exchanged, that is to say by simply pulling the pulling strip of the uppermost plate of the pile is moved backwards, descends along the rear side of the pile and finally is pulled forwards between the plates already exchanged and a support forced upwards elastically for the pile, the plates not sliding along each other or along the backing or protecting sheets 35 and not being exposed to injury.

The invention relates to an arrangement of photographic plates of this type and has for its object to simplify and cheapen the 40 arrangement by reducing the size of the backing sheets to substantially that of the plates, the backing sheets not being any more required to follow the pulling strips.

A further object of the invention is to 45 enable the arrangement to be used also in case that the plates have to be actuated for exchanging not by pulling strip but in any other manner say by a pusher.

The essence of the invention consists in 50 that the protecting sheet of the uppermost plate is directly connected to or directly passes into the backing sheet of the plate next below at the rear edge of the latter. Preferably these two sheets are made in one 55 piece bent around the rear edge of the next lower plate without being attached thereto.

If in this case pulling strips have to be used for exchanging purposes such pulling strips are secured to the front edge of the plates, the same as the protecting and back- 60 ing sheets and are located between the back- ing and protecting sheets of the individual plates and extend from the front edge of each plate to its rear end, down the rear side of the pile and then again forwards to 65 the pulling slot.

In the drawing a constructional form of the invention is shown by way of example, in which pulling strips are used.

Fig. 1 is a diagrammatical vertical section 70 of a pile consisting of three superposed plates, Fig. 2 is a perspective view on a smaller scale of two plates of the pile drawn apart.

Figs. 3 to 7 show various positions in ex- 75 changing two successive plates.

To the front edges 2, 12, 22 of each of the plates 1, 11, 21 respectively is secured a backing sheet 6, 16, 26 respectively in the example shown a pulling strip 4, 14, 24 80 respectively and a protecting sheet 3, 13, 23 respectively, the backing and the protecting sheet of each plate are approximately of the same size as the plate itself and are made of a sufficiently strong and flexible material 85 impervious to light, for instance of black paper. According to the invention the pro- tecting sheet 3, 13, 23 of each plate is di- rectly connected to or passes into the back- ing sheet 16, 26 of the next lower plate. 90 Preferably the two sheets are made in one piece that is bent around the rear edge of the next lower plate.

Fig. 2 shows a perspective view of this 95 arrangement.

If, starting from Fig. 1, the pulling strip 4 of the uppermost plate 1 is pulled out of the pulling slot 31 of the box 30, the plate 1 first moves backwards its back face being 100 protected by the backing sheet which is mounted on such back face and therefore cannot slide along the same, and at the same time is held out of contact with the top face of the lower plate 11 by the protecting sheet 3 of such plate 1. But also the pro- tecting sheet 3 can neither slide along the bottom face 1 being secured to its front edge, nor along the top face of the next lower plate 11 because it rolls off this top face as is clearly seen from Figs. 3, 5 and 6. 110 Then the plate descends on the rear side of the pile and slips as the pull on the pulling

strip 14 is continued below the pile support 31 and under the pulling strip 14 of the next lower plate, the protecting sheet 3 of the plate 1 being folded over to its top face and spread out smoothly thereon without sliding on the top face of this plate, as is clearly seen from Figs. 3 and 4. If then the pulling strip 14 of the following plate is pulled the operation above described is repeated as is seen from Figs. 4, 5 and 6 and if the plate 11 slips between the plate 1 and the pulling strip 24 of the next lower plate a loop 17, Fig. 6 is formed between the backing sheet 16 of the plate 11 and the protecting sheet 3 of the plate 1 just previously exchanged the backing sheet 16 being directly connected to the protecting sheet 3, such loop 17 is sufficiently retained by the rear edge of the plate 1 for preventing the protecting sheet 3 from shifting along the top face of the plate 1. It is simply the backing sheet 16 of the plate 11 that slides together with the latter and hence without sliding along the latter on the protecting sheet 3 of plate 1, the protecting sheet 3 not being capable of sliding on the plate 1 (Fig. 6). Finally the backing sheet 16 of the plate 11 is folded down on the protecting sheet 3 of the plate 1 as shown in Fig. 7. The same operation is repeated on exchanging the following plates.

If desired, the backing sheet and the protecting sheet of each individual carrier may be likewise made in one piece folded down on the front edge of such carrier and attached to it the pulling strip being arranged between the protecting and the backing sheet.

The present arrangement of the plates therefore warrants a perfect protection against mechanically injuring the plates in exchanging no matter whether the coating sensitive to light is on the top or on the bottom face of the plates. This arrangement also prevents an undesirable access of light. The pulling strips shown in the drawing are not a necessary element of the present arrangement of the plates; the plates might be actuated by pushers or otherwise.

The length of each protecting sheet plus that of the backing sheet connected thereto must somewhat exceed in length the double length of the plate because as shown in Fig. 4 after exchanging a plate the backing sheet of the next lower plate must pass round the rear side of the pile.

What we claim is:

1. In a pack of superposed photographic carriers of sensitized coatings the combina-

tion of a plurality of such carriers, a backing sheet and a protecting sheet attached to the front edge of each of such carriers, the backing sheet of each carrier being arranged between such carrier and the protecting sheet of the same and on the same side thereof, the rear end of the protecting sheet of each carrier being connected to the rear end of the backing sheet of the next lower carrier. 65 70

2. In a pack of superposed photographic carriers of sensitized coatings the combination of a plurality of such carriers, a backing sheet and a protecting sheet attached to the front edge of each of such carriers, the backing sheet of each carrier being arranged between such carrier and the protecting sheet of the same and on the same side thereof, the protecting sheet of each carrier and the backing sheet of the next lower carrier being integral with each other and meeting in a rear fold. 75 80

3. In a pack of superposed photographic carriers of sensitized coatings the combination of a plurality of such carriers, a backing sheet and a protecting sheet integral with and folded down on each other and attached to the front edge of each of such carriers, the backing sheet of each carrier being arranged between such carrier and the protecting sheet of the same and on the same side thereof, the protecting sheet of each carrier and the backing sheet of the next lower carrier being integral with each other and meeting in a rear fold. 85 90 95

4. In a pack of superposed photographic carriers of sensitized coatings the combination of a plurality of such carriers, a backing sheet and a protecting sheet attached to the front edge of each of such carriers, the backing sheet of such carrier being arranged between such carrier and the protecting sheet of the same and on the same side thereof. The rear end of the protecting sheet of each carrier being connected to the rear end of the backing sheet of the next lower carrier and a pulling strip for each carrier attached to the front edge thereof and interposed between the protecting and the backing sheet of such carrier, such pulling strip extending to the rear edge of it passing down along the rear edges of the carriers below the same and then forwards again below the pulling strip of the next upper carrier to the pulling slot. 100 105 110 115

In testimony whereof we affixed our signatures.
